UNITED STATES PATENT OFFICE.

ALBERT EDGAR BLACKMAN, OF MOUNT VERNON, NEW YORK.

MAIL BOX.

Application filed August 16, 1924. Serial No. 732,515.

The invention is a mail-box made up of a series of individual compartments or units, each compartment having two doors, one for the use of the postman for depositing the mail and the other for the use of the individual to whom the compartment is assigned. The postman's doors, for the series of compartments, are united to each other in a suitable manner so that one lock 10 will lock all of his doors and they can all be moved together.

A particular object of the present invention is to simplify the construction of the various parts of the box and to facilitate their assembly. Instead of using the ordinary two leaf hinge for the doors they are provided with a pintle rigidly fastened to them. The pintle is provided with ends projecting beyond the door. When the box 20 is folded and assembled these ends are engaged in suitable notches which act as bearings in which the door can rotate. The sheet metal of the box is so cut and provided with projections that the bending and 25 welding together of its parts is simplified.

The above and other objects and advantages will become apparent upon a study of the description and drawing in which:

Figure 1 is a front elevation of the box; 30 Figure 2 is a broken section taken along the line 2—2 of Figure 1; Figure 3 is a broken section taken above the line 3—3 of Figure 1; Figure 4 is a horizontal section taken through the left hand compartment of Figure 1 below the pintle of the lower door and shows an alternative method of fastening the backing-plate to the wall-plate; Figure 5 is a development of a corner of the sheet metal backing-plate forming the rear of a 35 compartment; Figure 6 shows an alternative way of fastening the pintle to the door by means of a bracket, and Figure 7 is a section along the line 7—7 of Figure 6.

The box comprises a wall-member composed of wall-plates 8 of sheet metal, each wall-plate having fastened to it a bent up backing-plate 9, one wall-plate 8 and plate 9 for each compartment 10, the drawing showing three of them. A developed corner 45 of one of these backing plates 9 is shown in Figure 5, the other three corners being similar. Flap 11 is bent along line 16 at right angles to the main portion of plate 9. Flap 12 is bent along line 17, also at right angles to the main portion of plate 50 9. Lap 14 is bent at right angles to flap 9. Lap 14 is bent at right angles to flap

11 along the dotted line. In a similar manner flap 13 is bent at right angles to flap 12. Projection 15 is bent at right angles also to flap 12. When the various flaps and 60 other parts have been bent into position, projection 15 comes down over the outside of flap 11 and parallel thereto. Notch 18 is provided to act as a bearing for one end of pintle 19 when the compartments and 65 doors 20 and 21 are assembled as will be explained. Each door 20 and 21 has a pintle 19 spot-welded to it and as said pintles are longer than the width of the doors, their 70 ends project beyond the side of the doors.

Projection 15 is spot-welded to the outside of flap 11. There being four such projections and two flaps each, 11 and 12, a rectangular box is thus formed open on one side. This open-sided box is now in my 75 preferred form, spot-welded along laps 13 and 14 to wall-plate 8, opposite the openings for doors 20 and 21. Before the spot-welding and bringing together of the open-sided box with wall-plate 8, the projecting 80 ends of pintles 19 of doors 20 and 21 were slipped into place in notches 18.

Each door 21 is provided with a lock 22 at its lower end, the left hand lock 22 only being shown somewhat in detail. To the 85 upper end of each door 21 a pintle 19 is fastened, preferably welded, the one for the left hand door only, being shown. The doors 20 are rigidly fastened to a cross bar 24. Each door 20 is provided with a pintle 90 19, preferably welded to its lower edge, the pintle 19 for the left hand door 20 only being shown. The center door 20 is provided with a lock 25.

Instead of spot-welding backing plates 95 9 to wall-plate 8, they can be riveted to it as shown by rivets 26 in Figure 4. Also instead of welding pintles 19 to doors 20 and 21 directly, they can be held to them by means of a number of brackets 27 which 100 are welded to the doors, one of these brackets 27 being shown in Figures 6 and 7.

The compartments 10 are braced together top and bottom by a bar 28 bolted to them.

In operation, the postman unlocks lock 105 25 pulling out all doors 20 at once. He then deposits the mail in the proper compartments 10. Later on, the individual owners of the compartments each with a different key opens his lock 22 and removes his mail. 110

I claim:

1. In a mail box, a compartment consist-

ing of a wall-plate having a pair of openings one above the other, an open-ended box rigidly secured against said wall-plate in register with said pair of openings and doors for said openings carrying lateral projections near their ends adapted to act as pivots, said open-ended box being provided with notches along its free edges, into which, said lateral projections are inserted before 10 said box is fastened to the wall plate.

2. In a mail box, a compartment consisting of a wall-plate, an open-ended box adapted to be rigidly fastened to the wall-plate, a door for said wall plate, consisting of a sheet of metal plate with a rod fastened to it, said rod projecting beyond the sides of the door, said open-ended box being provided with notches in its free edges into which the projecting ends of said rod are 15 inserted before said box is fastened to the wall-plate.

3. A mail box provided with a plurality of mail receiving compartments, each having two separate openings in its front wall, an 25 individual door for the removal of mail for closing one of said door openings of each compartment, a lock for each of said individual doors, each of said compartments being provided with a master door section for closing 30 the other of said door openings, and means for permanently and rigidly uniting said master door sections to form a master door, said means moving bodily away from the compartment with the master door sections, 35 when the master door is opened, one of said master door sections being provided with means for attaching a master door lock.

4. A mail box provided with a plurality of mail receiving compartments, each having two separate openings in its front wall, an 40 individual door for the removal of mail, for closing one of said door openings of each compartment, a lock for each of said individual doors, each of said compartments being provided with a master door section for closing 45 the other of said door openings, and a part extending across portions of each of said master door sections and being rigidly and permanently connected thereto

to form a master door moving as a unit, 50 said part moving bodily away from the compartment with the master door sections, when the master door is opened, one of said master door sections being provided with means for attaching a master lock thereto, 55 said master door sections tending to remain in open position when opened.

5. A mail box provided with a plurality of mail receiving compartments, each having an opening in the lower portion of its 60 face for the removal of mail and a separate opening of substantially the same area located above the first mentioned opening for the insertion of mail, an individual door provided with an individual lock for closing 65 each of said lower openings, a master door section for closing each of said upper openings, said sections hinged adjacent their lower edges and opening outwardly and a bar rigidly secured to and connecting all of 70 said master door sections.

6. A mail box provided with a plurality of mail receiving compartments, each provided with an aperture in its front wall for the insertion of mail, a master door section 75 for closing each of said apertures and hinged, and a connecting bar extending across all of the master door sections and rigidly united to each to form a master door, said connecting bar movable bodily 80 away from the compartment with the master door sections when the master door is opened, one of said master door sections being provided with means for attaching a master lock thereto, and each of said compartments being provided with independent 85 means in its front wall for withdrawing the mail deposited therein.

7. In a mail box the combination, with a plurality of units each comprising a receptacle having a face plate, provided with an individual door and a master door section located above the individual door, of means 90 for permanently uniting a plurality of said units, and a connecting bar permanently and 95 rigidly uniting the master door sections of the connected units for joint operation.

ALBERT EDGAR BLACKMAN.
